UNITED STATES PATENT OFFICE

142,107

DESIGN FOR A COMBINATION BABY BATH AND DRESSING STAND

Katherine H. Morrey, Chicago, Ill.

Application April 3, 1944, Serial No. 113,129

Term of patent 14 years

(Cl. D33—14)

To all whom it may concern:

Be it known that I, Katherine H. Morrey, a citizen of the United States, residing at Chicago, in the county of Cook and State of Illinois, have invented a new, original, and ornamental Design for a Combination Baby Bath and Dressing Stand, of which the following is a specification, reference being made to the accompanying drawings, forming a part thereof, in which:

Fig. 1 is a perspective view of a combination baby bath and dressing stand, showing my new design, the baby bath being illustrated in its normal inwardly recessed position;

Fig. 2 is a perspective view of the article showing the baby bath in its outwardly extended position;

Fig. 3 is an end elevational view thereof as seen from the left-hand end in Figs. 1 and 2, the

baby bath being shown in its outwardly extended position;

Fig. 4 is a front elevational view;

Fig. 5 is an end elevational view as seen from the right-hand end in Fig. 4, the baby bath being shown in its outwardly extended position; and

Fig. 6 is a top plan view of the article as illustrated in Figs. 3, 4 and 5.

The present design is characterized by the bath unit in its relation to and association with the dressing stand portion of the design all as shown.

I claim:

The ornamental design for a combination baby bath and dressing stand, substantially as shown and described.

KATHERINE H. MORREY.
